UNITED STATES PATENT OFFICE.

LEONARD F. MURKIN, OF CHICAGO, ILLINOIS.

VARIABLE HIGH-RESISTANCE ELEMENT AND METHOD OF MAKING THE SAME.

Application filed April 3, 1926. Serial No. 20,618.

My invention relates to new and useful improvements in high resistance elements and a method of making the same, and has for an object to produce a high resistance element which may be used in a gridleak, 5 potentiometer, or other similar article in which there is embodied a high resistance element.

Still another object of the invention is to 10 provide a method whereby the high resistance elements may be manufactured quickly, which elements have a greater current capacity than most of these variable high resistance elements now in use.

Now that B battery eliminators have come 15 into general use, it is necessary to produce a high resistance element that has a relatively high current capacity and will not deteriorate with use.

Still another object of the invention is 20 to provide a high resistance element made of a core and a plurality of resistance strips so that the proper ohmage may be obtained, and at the same time, the current carrying 25 capacity may be built up to the desired value.

Still another object of the invention is to 30 provide a high resistance, made up of a core and a plurality of resistance strips which are tightly held by a high resistance wire over which a movable arm operates, so that the high resistance strips may not be effected in any way by constant use.

Still another object of the invention is to 35 construct a high resistance element which has a relatively high capacity so that when used with a B battery eliminator, the resistance element will safely carry the amperage, and at the same time allow enough 40 milli-amperes to pass through the high resistance element to properly operate the set.

Still another object of the invention is 45 the method of making a high resistance element as will be shortly explained, so that all the parts will be tightly held together, and there being no possibility of any of the parts deteriorating or separating when in use.

With these and other objects in view, the 50 invention consists in certain new and novel arrangements and combination of parts as will be hereinafter more fully described and pointed out in the claims.

Referring now to the drawings, showing

a preferred embodiment and several forms 55 of use of the high resistance elements.

Fig. 1 is a view of a fiber core and two 60 resistance strips.

Fig. 2 is a similar view, but with the core and resistance strips assembled, and a high 65 resistance wire spirally wound about the same.

Fig. 3 shows a further step in the manufacture of the high resistance element, the turns of the spiral wire being cut through- 70 out the length of the element.

Fig. 4 is a side elevation of the high resistance element showing a fixed post at one 75 end and a slideable clip at the other for varying the resistance.

Fig. 5 shows the high resistance element 80 mounted in a gridleak shell, and

Fig. 6 is a similar view showing the high 85 resistance used in a potentiometer.

Referring now more particularly to Figs. 70 1 to 6, inclusive, there are shown the several parts which, when assembled, form the complete resistance element A. To provide a proper stiffness for the element, I employ a fiber core 1 upon which is placed two or 80 more strips 2 and 3 which are impregnated or saturated with India ink or any other suitable form of carbon to provide the necessary high resistance. After these strips have been placed upon the core, a wire 4 is 85 spirally wound around the core and resistance strip 2 and 3 to tightly bind the several parts together. This wire may be of high resistance, such as German silver, or any other form of similar wire, and after the 90 same is tightly wound about the several parts, the element A is placed between rollers (not shown) to press and partly embed the wire within the fiber strip and tightly press against the outer of the high 95 resistance strips 3.

By using a flexible fiber core, the requisite stiffness for the element is obtained, and at the same time, due to its composition, it allows the wire, when tightly wound about 100 the element, to become embedded for a slight distance in the core when the element is subjected to the pressure of a suitable set of rollers.

It is necessary and essential that the 105 turns of the wire be embedded in the fiber core when wound about the element, as, due to the high ductility of the wire, they have a

tendency to uncoil and spring from place unless they are embedded to some degree in the core. Furthermore, each turn of the wire has to be severed so that the current cannot simply pass through the turns from one end to the other, and this severing action will have a tendency to loosen the tension of the wire about the element unless the several turns are embedded within the core. In fact, after the turns are severed, I again run the element through rollers, as will be hereinafter mentioned.

I have only shown in the drawing two resistance strips 2 and 3, as bound to the core, but it is to be understood that three, four, or even five similar strips might be used to obtain the ohmage and capacity desired.

There is an advantage in using a multiplicity of resistance strips, inasmuch as the cross sectional area is increased, and in turn the current carrying capacity is increased. A heavy saturated resistance strip, such as 2 or 3, if employed, we will say, would provide 100,000 ohms resistance, but the capacity of the strip would be relatively low. With the present invention, I employ a plurality of resistance strips so that their combined resistance will provide 100,000 ohms resistance, and at the same time the current carrying capacity is much greater than if one highly saturated element was used, thus allowing the element to be used with B battery eliminators or with a relatively high plate current and allowing the requisite number of milli-amperes to pass therethrough to properly operate the set.

Furthermore, by using a core and plurality of resistance strips, and binding the same, the resistance strips are held in a tight contact, which, of course, is an advantage in a unit of this kind.

After the element has been tightly wound, as above described, I then take a cutter (not shown) with two cutting edges and run it lengthwise of the core at the rear thereof, and sever each turn of wire along the lines 5 and 6. After this, the element as a whole is again passed through rollers (not shown) to press the severed turns of the wire again tightly within the core. This is done, as although the element has previously been passed through rollers, the cutting action may have slightly loosened some of the turns, and the second rolling operation will again properly embed them within the fiber core and tightly bind the resistance strips to the core.

The resistance elements may then be used as shown in Fig. 4, that is, a fixed post 7 may be attached to one end of the resistance element, while slidably mounted near the opposite end may be a clip 3 to which a conducting wire 9 may be secured, and the variable resistance will, of course, be obtained by

sliding the clip along the resistance element A. Any wear, of course, will fall on the wire, rather than on the resistance strips, thus providing a long life for the element as a whole.

Inasmuch as the turns are all severed, and the several turns are not in contact with each other, no current will pass from one turn to the next turn through the wire itself, and there will be no perceptible noise in the output of the set when the resistance is varied by the movement of the slideable clip.

In Fig. 5, I have shown the resistance element A mounted in a gridleak shell 10, the resistance element being circular in outline, and the arm 11 rotatable about the element to vary the resistance as desired. In Fig. 6, I have shown a resistance element A mounted in a similar shell 12 having the arm 13 contacting with the wire of the resistance element, and in this instance, the unit is used as a potentiometer, the connection 14 being made from the center binding post 15, the binding post 15 being connected with a B battery or B eliminator, (not shown) or to other desired places in the circuit, while the binding posts 16 and 17 are connected with the ends of the resistance element A, so that the A plus and the A minus may be connected to the binding posts 16 and 17.

It will be noticed that in either instance that any wear from the rotation of the arms 11 or 13 will be taken up by the wire 4 so that the resistance strips 2 and 3 are protected and will not flake, wear, or disintegrate from use.

From the foregoing it will be seen that I have provided a resistance element wherein a fiber core is used, and to which is tightly bound a plurality of resistance strips, the ohmage of the resistance being built up as desired, while the current carrying capacity is also increased, due to the increase of cross sectional area, thus providing a high resistance element with a relatively high current carrying capacity. Of course, I can make the resistance element of varying ohmages say from 100, ohms to 10 megohms, depending on the resistance of the strips employed.

As pointed out in the specification, it is preferred and desired to use two or more resistance strips tightly bound to a core, but it might be possible to use a fiber strip or a resistance strip which in itself would have enough carbon to provide a high resistance and at the same time be soft enough to have the wire embedded in the one strip. My method, therefore, could be used with such an element provided, an element could be found that is stiff enough to give the necessary rigidity; soft enough to have the wire embedded therein; and a carbon content which would form the necessary high resistance.

I am aware that it is old to wrap a fiber strip with wire, sever the turns and place a resistance element against the so wrapped strip, and I am also aware that it is old to spirally wind a core and after cutting the several turns of the wire impregnate the strip with a high resistance element, but I am not aware of a resistance element comprising a core having layers of resistance strips placed thereon and then tightly bound with a wire, after which the wire is cut, and the current carrying capacity made as high as desired by the increase of cross sectional area of the several resistance element strips.

16 It will also be understood that these elements may be made up of any desired ohmage and capacity, and that they may or may not be used with arms or clips for varying the resistance.

20 Having thus described my invention, what I claim as new and desire to secure by Letters Patent is:—

1. The method of making a high resistance element having a relatively high capacity, consisting of assembling a fiber core and a plurality of high resistance strips, the fiber core forming one outer side of the element, one of the resistance strips forming the opposite outer side of the unit, binding the several parts together by winding a wire spirally about the said parts, the turns of the wire being slightly spaced from each other, subjecting the built-up element to a set of compression rollers to slightly embed the turns of the wire within the core, severing the turns of the wire throughout the length of the element, and on the outer surface formed by the fiber core, subjecting the element again to a set of compression rollers to tightly hold the parts together and to more firmly embed the wire within the core.

2. The method of making a high resistance element having a relatively high capacity which consists in assembling a strip of fiber core and a plurality of resistance strips whose combined resistance when assembled will give the desired resistance and whose cross sectional area is such that the desired capacity will be obtained, binding the core and resistance strips together so that the resistance strips are adjacent to each other and one of the resistance strips being adjacent said core, the binding medium being a high resistance wire wound spirally about the said core and strip and whose turns are slightly spaced from each other, subjecting the built-up element to pressure to embed the turns within the core and to contact with one of the resistance strips, and severing the turns of the wire to prevent the current from passing from one end thereof to the other.

3. The method of making a high resist-

ance element having a relatively high capacity which consists in assembling a strip of fiber core and a plurality of resistance strips whose combined resistance when assembled will give the desired resistance, and whose cross sectional area is such that the desired capacity will be obtained, binding the core and resistance strips together so that the resistance strips are adjacent to each other and one of the resistance strips being adjacent said core, the binding medium being a high resistance wire wound spirally about the said core and strip and whose turns are slightly spaced from each other, subjecting the built-up element to pressure to embed the turns within the core and to contact with one of the resistance strips, severing the turns of the wire to prevent the current from passing from one end thereof to the other, and again subjecting the element to compression to more securely embed the wire in the core and to more tightly clasp the parts together.

4. A high resistance element comprising a semi-flexible fiber core, a plurality of separate flexible high resistance strips placed on one side of said core, a wire spirally wound about said core and strips, the turns of wire embedded within the said core and a portion of each turn of the wire removed on the free side of the said core.

5. A high resistance element comprising a fiber core, a plurality of high resistance strips placed on one side of the core, the sum of the resistance strips providing the desired ohmage, and the cross sectional area of the plurality of strips providing a relatively high capacity, the said parts being tightly held together by a spirally wound wire, the turns of the wire being slightly spaced from each other, embedded within the core and contacting with a surface of one of said resistance strips, and a portion of the turns of said wire being removed along one surface of the core.

6. A high resistance element comprising a flexible fiber core, a plurality of strips impregnated with carbon to form a high resistance, the said resistance strips lying adjacent one surface of said core, the combined ohmage of said strips giving the desired ohmage and the cross section of said strips providing a relatively high current carrying capacity, a wire spirally wound about the said core and said resistance strips for tightly holding the said resistance strips to each other and to said core, the wire embedded in the outer surface and upper and lower edges of said core, the turns of said wire being slightly spaced from each other, and a portion of each turn being removed.

In testimony whereof I affix my signature.

LESLIE F. MUTER.
